UNITED STATES PATENT OFFICE.

ELISEO DEL VALLE, OF BROOKLYN, NEW YORK, ASSIGNOR OF ONE-HALF
TO AUGUSTUS R. O. SCHABBEHAR, OF SAME PLACE.

FENDER ATTACHMENT FOR STREET-CARS.

SPECIFICATION forming part of Letters Patent No. 540,644, dated June 11, 1895.

Application filed August 2, 1894. Serial No. 519,236. (No model.)

To all whom it may concern:

Be it known that I, ELISEO DEL VALLE, a citizen of the Kingdom of Spain, residing in the city of Brooklyn, in the county of Kings

5 and State of New York, have invented certain new and useful Improvements in Fender Attachments for Street-Cars, of which the following is a specification.

This invention relates to an improved fender-attachment for electric, cable and other surface-cars, which fender-attachment is located in front of the dash-board of the car, and placed in such position that as soon as the forward-extending guard-arms of the attachment abut against an obstruction on the track, the fender-net is immediately extended in forward direction so as to scoop up the obstruction and prevent it from being injured by the car; and the invention consists of a 10 fender-attachment for street-cars, which comprises an upright main-frame that is provided with means for attachment to the dash-board of the car, forward-extending guard-arms applied to a transverse piece pivoted to the 15 main-frame, a flexible guard-cord that extends from folding side-arms over the ends of the guard-arms, and a fender-net that is stretched over the main-frame, a U-shaped frame fulcrumed at its upper ends to curved 20 arms of the main-frame, the upper ends of said frame, as well as the upper ends of the pivoted side-arms, being connected by suitable springs and retained in closed position on the main-frame by means of locking-cams, 25 so that as soon as the elastic guard-cord strikes the obstruction on the track, the fender-net is extended in forward and lateral position and supported on shoulders of the forward-extending arms, so that the middle 30 portion scoops up the body or other obstruction, while the backwardly-inclined side-portions ward off any obstruction and push the same sidewise off the track, as will be fully described hereinafter and finally pointed out 35 in the claims.

In the accompanying drawings, Figure 1 represents a perspective view of a car with my improved fender attachment, showing the latter in its normal position on the dashboard 40 of the car. Fig. 2 is a perspective view of the fender attachment drawn on a larger scale

and showing it extended for scooping up an obstruction on the track. Fig. 3 is a front elevation of the fender attachment, and Fig. 4 a side elevation of the same.

55

Similar letters of reference indicate corresponding parts.

Referring to the drawings, A represents the dash-board of an electric, cable or other car, to which my improved fender-attachment is 60 applied.

The fender-attachment consists of an upright main-frame B, which is provided at its upper and lower ends with hooks b b', by which the main-frame is rigidly attached to a 65 frame A' of the dash-board of the car or to eyes on the same or in any other sensible manner.

To the upper connecting-rail of the main-frame B are fulcrumed oscillating arms C, 70 which are connected with said rail by means of strong helical springs C'. To the lower ends of the fulcrumed and spring-actuated arms C are pivoted laterally-extending arms C², which are guided in perforated lugs c³ of 75 the main-frame B, and which are retained, when pushed inwardly in the plane of the main-frame, by recessed locking-links D, which are pivoted to the outer ends of the arms C², on the lugs C³ of the main-frame B, 80 as shown in Figs. 3 and 4. When the arms C² are pushed inwardly, they are retained in locked position by the recessed ends of the links D on the lugs C³, and by the tension of the springs C', said arms being quickly moved 85 in outward direction as soon as the locking links D are released from the lugs C³.

To the lugs C³ at the lower end of the main-frame B is pivoted a transverse bar E, which is provided at right angles thereto with forward-extending guard-arms E', which carry at their front-ends guide-sleeves E² through which is extended a flexible guard-cord E³, of any approved material said guard-cord forming with the arms a guard-device that extends in front of the lower part of the dash-board and that is located close to the rails of the track, as shown in Fig. 1. The forward-extending arms E' are provided at their under sides, near the guide-sleeves E², with 90 downwardly-extending shoulders e, which serve to support the lower transverse part of 95 100

a U-shaped fender-frame F, the side-arms of which are fulcrumed to the forwardly-bent upper ends of the main-frame B. The side-arms of the fender-frame F are extended by 5 short crank-arms f above the fulcra, and are each connected by strong helical springs f' with fixed points on the main-frame B, said springs moving the fender-frame F in forward direction as far as permitted by the guard- 10 cord E³ so that the lower transverse part of the fender-frame F is retained by the shoulders e of the arms E'. To the outer ends of the laterally-movable arms C² are applied fixed forwardly-extending locking-arms f, 15 which engage the side-arms of the fender-frame F, when the latter is moved against the tension of its springs f' into vertical position in front of the main-frame, as shown in Fig. 4.

A fender-net N is stretched over the main- 20 frame and attached to the outer ends of the arms C² and the lower part of the fender-frame F, as shown clearly in Fig. 2. When the arms C² are pushed inwardly and locked by the recessed links D, and when the fender- 25 frame F is moved up toward the main-frame B, the fender-frame is locked in vertical position close to the main-frame B by the hooks f². The slack of the flexible guard-cord E³ is taken up by the pivoted links D when the 30 fender-frame is in locked position, while when the fender-frame F and fender-net N are in forward position, the guard-cord E³ is stretched taut when the fender-frame is retained by the shoulders e in forwardly-inclined position, as 35 shown in full lines in Fig. 3, and in dotted lines in Fig. 4.

When the fender-attachment is desired for use, it is hung on the front dash-board of the car and firmly secured by the hooks b b' to 40 the frame A'. The fender-frame F is then in upright position, its lower end being retained by the hooks f² engaging the lower part of the side-arms of the fender-frame, as shown in Fig. 4. In this position of the fender- 45 frame, the actuating-springs f' are set to tension, while the side-arms C² are pushed inwardly and their springs C' set to tension by the locking links D. The guard-cord that extends over the forwardly-extending arms E' 50 and their pivoted guide-sleeves E² is likewise set to tension by the rearward position of the locking links D, so that when the track is obstructed by a body, the latter is struck by the guard-cord, either at its transverse front-portion or at its backwardly-extending side- 55 portions, and thereby a tension exerted on the same, so that the links D are released, the side-arms C² moved instantly in lateral direction releasing the fender-frame F, and permitting the latter to be moved by its springs in forward direction, whereby the fender-frame is taken up by the stop-shoulder e, and the side and lower portions of the fender-net are stretched and placed in position to scoop 60 up the body or other obstruction on the track without injury to the same. The side-portions of the fender-net N serve to push the

obstruction sidewise clear of the track, so as to prevent accidents or other injury to the same. When the obstruction is removed, the 70 fender-frame and side-arms are returned into their normal position and locked by the links D and hooks f², the links also imparting the necessary tension to the flexible guard-cord, while the fender-net is folded up between the 75 main and fender-frames, as shown in Fig. 1.

When the car is to be run in the opposite direction, the entire fender-attachment is removed from one dash-board and placed in position on the other dash-board, for which purpose the forwardly-extending guard-arms E' are first moved with the flexible guard-cord into the upward position between the fender-frame, as shown in dotted lines in Fig. 4, in which position the whole fender-attachment 80 can be readily removed by the conductor and replaced in position on the dash-board at the opposite end of the car. The forward-extending guard-rods and the flexible guard-cord are then lowered again after which the 85 attachment is again ready for use, it being called into action whenever the guard-cord strikes an obstruction, either by its transverse front portion or by its inclined side-portions, so that the obstruction is either scooped 90 up or pushed sidewise of the track, and thereby 95 accidents and injuries prevented.

Having thus described my invention, I claim as new and desire to secure by Letters Patent—

1. A fender-attachment for cars, comprising an upright main-frame, means for attaching said main-frame to the dash-board of the car, spring-actuated and laterally-swinging side-arms, a spring-actuated fender-frame fulcrumed to forward-extending arms of the main-frame, a transverse bar pivoted to the lower part of the main-frame, forwardly-extending guard-arms applied to said pivoted bar, a flexible guard-cord extending over the front-ends of said forwardly-extending arms, a fender-net stretched on the main and fender frames and connected to the outer ends of the laterally-swinging side-arms, and means for locking the fender-frame and laterally-swinging side-arms close to the main-frame, and release the same when an obstruction strikes the guard-cord, substantially as set forth.

2. A fender-attachment for cars, comprising an upright main-frame, means for attaching the same to the dash-board of the car, fulcrumed and spring-actuated arms swinging in the plane of the main-frame, laterally-swinging side-arms pivoted to the lower ends of said fulcrumed arms, a spring-actuated fender-frame, the side-arms of which are fulcrumed to the upper ends of the main-frame, forwardly-extending guard-arms, a flexible guard-cord guarded at the ends of said arms, a fender-net stretched over the main and fender-frames and attached to the outer ends of the laterally-swinging side-arms, recessed locking links pivoted to the outer ends of the side-arms, and connected to guard-cord and lock-

ing hooks on the side arms, for holding the fender-frame in locked position close to the main-frame, substantially as set forth.

3. The combination of an upright main-frame, provided with forwardly-bent arms at its upper end and guide-lugs at its lower end, a U-shaped fender-frame fulcrumed to said arms, springs for connecting the upper ends of the fender-frame with the main-frame, a transverse bar pivoted to the lower part of the main-frame, forwardly-extending guard-arms attached to said transverse bar, downwardly-extending shoulders at the front-ends of the guard-arms, a guard-cord extending over the front ends of the guard-arms, locking device

on the laterally-extending side-arms, adapted for locking the fender-frame to the main-frame, locking links pivoted to the outer ends of the side-arms and connected to the guard-cord, said locking links having recesses for engaging the guide-lugs for locking the side-arms and fender-frame and setting the guard-cord to tension, substantially as set forth.

In testimony that I claim the foregoing as my invention I have signed my name in presence of two subscribing witnesses.

ELISEO DEL VALLE.
